UNITED STATES PATENT OFFICE.

EDUARD ZICKWOLFF, OF SAARBRÜCKEN, ASSIGNOR, BY MESNE ASSIGNMENTS, TO GEBRÜDER MÜGEL, OF ST. JOHANN-ON-THE-SAAR, GERMANY.

HEAT-REGULATOR.

SPECIFICATION forming part of Letters Patent No. 365,220, dated June 21, 1887.

Application filed January 22, 1886. Serial No. 189,804. (No model.)

To all whom it may concern:

Be it known that I, EDUARD ZICKWOLFF, a subject of the Emperor of Germany, residing at Saarbrücken, Germany, have invented new and useful Improvements in Heat-Regulators, of which the following is a specification.

The object of my invention is to provide a new and improved regulator which automatically regulates the amount of heat admitted to a room, either keeping the temperature of the room constant or raising the same periodically.

The invention consists of an apparatus in which a volatile liquid vaporizing at the ordinary temperature is used, the vapors of which, as they expand under a higher temperature, act upon a column of mercury, which operates a device for opening and closing the inlet-valve for the heat, and also of a device for raising the temperature periodically.

The invention also consists of parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a front elevation, partly in section, of my improved regulator. Fig. 2 is a side elevation of the same. Fig. 3 is a sectional plan view on the line xx , Fig. 1. Figs. 4, 5, 6, 7, 8, and 9 are detail views, hereinafter more fully described.

The vapors or gases of a volatile liquid which vaporizes at an ordinary temperature expand when subjected to a higher temperature. In my improved apparatus I employ this principle in such a manner that when the volatile liquid, A, confined in a closed vessel, C, upon a body of mercury, B, vaporizes and the temperature of the air surrounding the vessel C increases, the vapors or gases exert their pressure upon the mercury, B, and force the same into a tube, D, which is fitted into the vessel C and extends nearly to the bottom of the same, and in which tube D the pipe E slides.

The pipe E supports and opens into the chamber F, which slides between stationary guides H H, and is counterbalanced by a weight, J. In the chamber F is placed a float, G, provided on its top with an upwardly-extending arm, G', which connects with a single-armed lever, L, (see Fig. 3,) fulcrumed on the shaft L', mounted in suitable bearings, L², secured to the top of the chamber T.

On the shaft L' is fixed a double-armed lever, M, which is provided on one end with a counter-weight, N, and on the other end carries a pulley, b. A similar pulley, c, is placed beneath the pulley b on the chamber F. Around these pulleys b and c is passed a cord, o, fastened at its upper end to the guide H at a, and at its lower end attached to a lever, d. The lever d is provided with a toothed segment, d', which meshes with the pinion d² on the valve d³ in the hot-air pipe d⁴.

A vertical shaft, K, revolves in suitable bearings attached to one guide H; and is provided with stops I, I', I², and I³, placed suitable distances apart and adjustable thereon by means of set-screws or other suitable means. The distances between the stops are greater or less, according to the desired increase of temperature. At the upper end of the shaft K is mounted the worm-wheel P, which is in gear with the worm S, mounted on a shaft, S', placed in suitable bearings attached to the guide H.

Above the worm-wheel P is placed and keyed to the shaft K a ratchet-wheel, Q, with which a pawl, e, engages, which pawl is pivoted to the worm-wheel P, as clearly shown in Fig. 8, so that a revolution of the worm S transmits motion to the shaft K by means of the worm-wheel P, carrying the pawl e, which engages with the ratchet-wheel Q. One end of the worm S is prolonged to form a drum, T, which is rotated by a cord and weight, R.

On the shaft S' is fixed a disk, U, and at the side of the same is placed an eccentric, V. The disk U is provided with a notch, U', in front of which is placed a lever, h, provided with a lug, g, which prevents the revolution of the disk U with the worm S and the drum T on the shaft S'. The said lever h is firmly

connected with a second lever, *i*, so as to form a single bent lever, pivoted at *k*. At the front end of the lever *h* is mounted a third lever, *l*, having a lug, *m*, which rests upon a support, 5 *W*. The lever *l* is held upright by a spring on the lever *h*, as shown in Fig. 6. *X* is an hour-wheel of a clock, (see Fig. 7,) provided with projecting pins adapted to engage the lever *l*.

10 The operation is as follows: The chamber *F* having been adjusted to the desired degree of heat required, now if an increase of temperature takes place, the mercury, *B*, enters the chamber *F* and raises the float *G*, which, by 15 means of the connections *G'* and *L*, causes the other end of the double lever *M*, carrying the pulley *b*, to swing downward in the direction of the arrow *a'*, whereby the lever *d* will close the valve *d'* and prevent the passage of more 20 heat into the room. The temperature of the room then falls to the desired degree. A scale, which has been determined by experiment, is arranged on one of the guides *H*, and facilitates the adjustment of the chamber *F* for a 25 certain degree of heat.

Instead of the pipes *D* and *E* being arranged so as to slide one within the other, they can be connected by a hose, as shown in Fig. 9, which will permit of the upward movement of 30 the chamber *F*.

If a periodical automatic increase of temperature is desired, one of the stops, *I*, is placed over a projection on the chamber *F* at the desired point indicated on the scale fixed on the 35 guides *H*, and the other stops, *I'*, *I''*, and *I'''*, are placed above the first stop at definite intervals, according to the desired increase of temperature, so that when a slight increase of temperature is desired the stops *I*, *I'*, *I''*, and 40 *I'''* must be placed nearer together, and when a greater increase of temperature is desired they must be placed farther apart. As the hour-wheel revolves, the pins projecting therefrom strike against the lever *l*, which is pressed from 45 its support *W*, so that the lever *h* falls down, and the lug *g* is displaced from the notch *U* in the disk *U*. The weight *R* causes a revolution of the drum *T* and of the worm *S*, so that the latter transmits a partial revolution 50 to the shaft *K*, which causes the stop *I* to move from the lug on the chamber *F*, which is then drawn upward by the counter-weight *J*. The partial rotation of the shaft *K*, before mentioned, places the second stop, *I'*, in position 55 to be engaged by the chamber *F*, so that the said chamber *F* is held under the second stop in its ascension until the second partial rotation of the vertical shaft, caused in the manner before described by the clock, permits the 60 chamber *F* to rise to the succeeding stop. The levers *l*, *i*, and *h*, which are displaced by the wheel of the clock, are brought back into their former positions by the eccentric *V* after each full revolution of the drum *T*, the said 65 eccentric pressing against the second lever, *i*, and thereby lifting the first lever, *h*, and its

connecting-lever *l* upon the support *W*, which prevents the further revolution of the disk *U*, the worm *S*, and the drum *T*. In the progressive ascent of the chamber *F*, the channel 70 or tube through which the heat enters the space is gradually opened to a greater extent by the lever *d*, and remains in this condition until the vapors created by the increased admission of heat cause the mercury to enter the 75 chamber *F*, thereby regulating the admission of the heat, as before described.

It will be understood that on the distances between the several stops *I*, *I'*, *I''*, and *I'''* depends the amount of the increase of the heat, 80 while the successive periods at which the increase of temperature takes place are dependent on the disengagement of the lever *l*, which is effected periodically by the clock mechanism. 85

Springs may be used instead of weights for producing the movements of the chamber *F* and the drum *T*. For convenience in winding the cord which carries the weight upon the drum *T*, the shaft *S'* is provided with the 90 crank-handle *T'*.

A partial rotation may be given the shaft *K* at stated intervals by means of the bevel gear-wheel *z*, attached to the lower end of the shaft *K* and meshing into the bevel gear-wheel *f'*, 95 placed on the shaft *f*, which is revolved by the crank-handle *f''*. By this construction the stops on the said shaft *K* may be turned in the path of the chamber *F* by hand.

Having thus described my invention, what I 100 claim as new, and desire to secure by Letters Patent, is—

1. In a heat-regulator, the combination, with a closed vessel for containing mercury and a volatile liquid, and a valve-operating lever, of a chamber communicating with said vessel, a float in the chamber, and means for operating the valve-operating lever by the rise and fall of the float, substantially as herein shown and described. 110

2. In a heat-regulator, the vessel *C*, containing mercury, *B*, and a volatile liquid, *A*, in combination with the pipes *D* and *E*, the sliding chamber *F*, the float *G*, the lever *M*, the rod *G'*, the lever *L*, the shaft *L'*, the pulleys *b* 115 and *c*, the cord *o*, and the valve-operating lever *d*, substantially as herein shown and described.

3. In a heat-regulator, the vessel *C*, containing mercury, *B*, and a volatile liquid, *A*, 120 the tubes *D* and *E*, and the chamber *F*, in combination with the float *G*, the connecting-rod *G'*, the lever *L*, fulcrumed on the shaft *L'*, mounted on the chamber *F*, the lever *M*, the pulleys *b* and *c*, the cord *o*, and the lever *d*, 125 operating the inlet-valve, substantially as herein shown and described.

4. In a heat-regulator, the counterbalanced chamber *F*, containing a float, *G*, which is operated by the vapors of a volatile liquid 130 acting on a body of mercury, the levers *L* and *M*, the pulleys *b* and *c*, the cord *o*, and the le-

ver d , in combination with the shaft K, the stops I, I', I², and I³, placed at suitable intervals on the shaft K, and means for partially rotating the said shaft, substantially as herein shown and described.

5. In a heat-regulator, the counterbalanced chamber F, the shaft K, the stops I, I', I², and I³, mounted on said shaft K, the worm-wheel P, the worm S, the drum T, and the cord and weight R, in combination with the ratchet-wheel Q, the pawl e, the disk U, the eccentric V, and the levers h , i , and l , substantially as herein shown and described.

6. In a heat-regulator, the shaft K, the worm-wheel P, the worm S, the drum T, the cord and weight R, and the disk U, having a notch, U', in combination with the eccentric V, the levers i , h , and l , and means for oper-

ating the lever l , substantially as herein shown and described.

7. In a heat-regulator, the shaft S', the drum T, the cord and weight R, the eccentric V, the disk U, having a notch, U', and a worm, S, in combination with the levers i , h , and l , pivoted at k , of which the lever h is provided with a lug, g , and the lever l with a lug, m , a support, W, and means for disengaging the lug m from the support W, substantially as herein shown and described.

20
In testimony whereof I have signed my name 30 to this specification in the presence of two subscribing witnesses.
